UNITED STATES PATENT OFFICE.

CARL OSCAR BERG, OF EVERETT, MASSACHUSETTS, ASSIGNOR TO UNITED METAL SEAL COMPANY, A CORPORATION OF MASSACHUSETTS.

MACHINE FOR PROVIDING CLOSURES WITH SEALS.

Application filed March 10, 1919. Serial No. 281,840.

To all whom it may concern:

Be it known that I, CARL OSCAR BERG, a citizen of the United States, and a resident of Everett, in the county of Middlesex and State of Massachusetts, have invented Improvements in Machines for Providing Closures with Seals, of which the following is a specification, reference being had to the accompanying drawings, forming part 10 thereof.

This invention relates to machines employed in the manufacture of bottle caps and other articles.

A type of bottle cap that may be produced 15 by the present embodiment of the invention is made of sheet metal which is dished somewhat and is provided with an annular flaring flange or skirt that is fluted about its edge. The dished portion of the cap is furnished with a cushioning member which 20 usually comprises a disk of cork. In order to prevent the contents of the bottle from coming into contact with the cushioning member, it is customary to apply a circular 25 seal or protecting member thereto of substantially the diameter of the end of the opening in the neck of the bottle. This seal is usually secured to the cushioning member by means of an annular flange formed 30 thereon which is inserted into a circular cut or scoring made in the cushioning member and is held therein by frictional contact with the walls of said scoring. Usually the seal is made of thin ductile metal having little 35 stability and hence the flange thereof cannot be depended upon to resist deflection if brought into contact with the surface of the cushioning member of the bottle cap. It is therefore important that the flange of 40 the seal should be brought into accurate registry with the scoring in the cushioning member before the seal and cushioning member are brought toward each other to introduce said flange into the scoring.

One object of the invention is to construct 45 a machine of the nature described so that a seal or protecting member having a flange or an extension may be accurately applied to a cushioning member of a bottle cap or other closing device used to close bottles, jars or other containers.

Another object of the invention is to construct 50 a machine of this nature so that the seal or protecting member may be made from a strip of suitable material; that the

cushioning member may be scored or provided with a receptacle for an extension of said seal; and that such operations may be so controlled that ultimately the said extension from said seal may be brought into registry with and be received by the scoring of said cushioning member.

Further objects of the invention will appear from the following description.

The invention consists in the means whereby the projection of the seal and the scoring or depression of the cushion member are brought into registry.

The invention also consists in the means for making the seal combined with the means 70 for scoring the cushion member and the means whereby accurate registry of the elements may be effected.

The invention also consists in such other novel features of construction and combination of parts as shall hereinafter be more fully described and pointed out in the claims.

Figure 1, represents a plan view of the machine.

Figure 2, represents a sectional view taken 20 on the line 2—2 of Fig. 1.

Figure 3, represents a horizontal sectional view taken on the line 3—3 of Fig. 2.

Figure 4, represents an enlarged sectional view taken on the line 4—4 of Fig. 1, of portions of the scoring means and cap holding means.

Figure 5, represents a sectional view taken on the line 5—5 of Fig. 4.

Figure 6, represents an enlarged detailed 90 sectional view taken on the line 6—6 of Fig. 1, of portions of the seal shaping mechanism.

Figure 7, represents a sectional view 95 mostly in elevation taken on the line 7—7 of Fig. 1 looking from the rear of the machine.

Figure 8, represents a detail sectional view taken on the line 8—8 of Fig. 1, of portions 100 of the mechanism for discharging the completed caps from the machine.

Figure 9, represents an enlarged detail sectional view taken on the line 9—9 of Fig. 1, of portions of a cap delivering mechanism, the parts thereof being shown in retracted position.

Figure 10, represents an enlarged sectional view taken on the line 10—10 of Fig. 1, of portions of the seal applying mechanism.

Figure 11, represents a plan view of a bot-

tle cap before the seal or protecting member has been applied thereto.

Figure 12, represents a similar view of the seal after the cushioning member has been scored.

Figure 13, represents a similar view with the seal applied to the cushioning member.

Figure 14, represents a sectional view taken on the line 14—14 of Fig. 13.

10 Similar characters of reference designate corresponding parts throughout.

Referring particularly to Figs. 1 and 3 of the drawings, the machine is provided with a driving shaft 10 that is driven from any suitable source of power by a driving pulley 12 mounted thereon, which pulley is adapted to be clutched to the shaft by means of a common type of clutching device 14. The driving shaft carries a bevel gear 16 which continuously drives a bevel gear 18 that is journaled on a stud 20 secured to the frame of the machine. The top side of the bevel gear 18 carries a roll 22 which cooperates with a radially slotted disk 24 to impart a uniform step by step movement to a shaft 26 to which the disk 24 is secured. The upper end of the shaft 26 carries a feed dial 28 which is in sliding engagement with a circular table 30 secured to the frame of the machine. The intermittently rotating shaft 26 also carries a gear 32, which, by operatively engaging gear teeth formed on the periphery of a carrier or table 34, intermittently rotates the table in timed relation to the feed dial 28. The table 34 in turn imparts a corresponding intermittent movement to a disk carrier or table 36 through the engagement of the gear teeth on the periphery of said table 34 with a gear 38 secured on the underside of the disk carrier or table 36. The table 36 is journaled on a stud 40 projecting from the frame of the machine and is held in place by a washer 42 which is secured to the stud by a cap screw 44.

The bottle caps which are indicated at a are presented to the machine from a suitable hopper through a chute 46, which is arranged to severally deliver the caps to recesses 48, formed in the periphery of the feed dial 28, which recesses cooperate with the top side of the circular table 30 and a peripheral flange 49 on the table to form pockets 50 for the bottle caps. The relative timing of the intermittent movements of the feed dial 28 and the rotating table 34 is such that the recesses 48 and suitable spaced pockets 52 on the table 34 are successively brought into registry after each movement of the dial and table and at a point beneath a plunger 54. (Fig. 2). When this occurs, the plunger 54 is depressed to force the caps down through an opening 56 in the circular table 30 and into one of the pockets 52 in the table 34. As the bottle

caps are being carried intermittently by the table 34, they are successively acted upon by a scoring device 58 (Fig. 4) which forms an annular scoring or cut b in the cushioning member c of the bottle caps. (Fig. 12). The caps are then successively transferred beneath a disk or seal applying device 60 (Fig. 2) which attaches a seal to the cushioning member by forcing the flange upon the periphery of the seal down into the annular scoring in the cushioning member. The caps are then successively carried by the table 34 to a seal setting device 64 (Fig. 10) which applies additional pressure to the seals, and thereafter the caps are successively ejected from the pockets in the table 34 and discharged from the machine through a chute 66 which is secured to the machine frame. The plunger 54, scoring device 58, seal applying device 60 and disk setting device 64 reciprocate in unison and in timed relation to the intermittent rotation of the table 34. To this end, said devices and plunger are carried by a vertically reciprocating plunger 70 (Figs. 1 and 2) which is actuated by means of an eccentric 72 carried by the driving shaft 10. The plunger 70 is guided by a bearing 71 in the frame of the machine and by rods 73, 73 secured to a cross bar 74 of the frame, which rods extend through apertures in lugs or brackets 75 projecting from the plunger 70.

The plunger 54 is provided with a head 76, Fig. 9, and its shank extends through and is guided in an aperture in a bracket 78 secured by bolt 80 to the reciprocating plunger 70. The plunger 54 is urged downwardly by a spring 84 coiled about a reduced portion of the shank of the plunger and interposed between a shoulder 86 formed on the shank, and a sleeve 88 threaded into said aperture in the bracket 78. The downward movement of the plunger 54 is limited by nuts 90 threaded on the upper end thereof.

The scoring device 58 (Figs. 1, 4 and 5), comprises a scoring or cutting tool 92 secured to the lower end of a spindle 94 which is mounted to rotate in a bracket 96 secured by bolts 98 to the reciprocating plunger 70. The pressure exerted by the cutting tool 92 is resisted by a thrust bearing 99 on the spindle 94, which bearing is interposed between a nut 100 threaded on the spindle and a horizontal arm 101 which forms a part of the bracket 96. A slight clearance is provided between the upper surface of the part 100 and the lower surface of the bracket 101. The spindle 94 is rotated continuously during the operation of the machine by a gear 102 secured to the upper end thereof, which gear is operatively engaged by a gear 104 secured to the upper end of a shaft 106 that is journaled in the bracket 96. The gear 104 is driven through

pins 108 by a block 110 secured to the lower end of a shaft 112. The shaft 112 is journaled in a bracket 114 that is secured to the cross bar 74 of the machine frame. 5 A pinion 118 is secured to the upper end of the shaft 112 and is operatively engaged by a gear 120 that is secured to the underside of a sprocket wheel 122, journaled on a stud 124 which projects upwardly from the bracket 114. This sprocket wheel 122 is driven by a sprocket chain 126 which connects the sprocket wheel with a sprocket wheel 128 carried by the upper end of a vertical shaft 130 that is journaled in the frame of the machine. The shaft 130 is in turn driven by a bevel pinion 132 secured to its lower end, which meshes with a bevel gear 134 secured to the main shaft 10 of the machine. 10 15 20 25

In order to allow for the reciprocation of the scoring cutter 92, and still effect continuous rotation thereof, the pins 108 that connect the gear 104 to the head 110 are secured at their lower ends to the gear 104 and their upper ends are free to slide in apertures in said head.

When the scoring cutter 92 is brought down into engagement with the cushioning member of a bottle cap, as shown in Fig. 4, 30 it is necessary to firmly hold the cap against rotation by the rotation of the cutter 92, otherwise the scoring would not be properly formed. Accordingly, the illustrated machine is provided with a presser foot which 35 firmly grips a cap adjacent the periphery of the cutter when the scoring tool is brought into engagement with the cap. This presser foot comprises a sleeve 136 that surrounds the cutter and its upper end extends into and is guided by an annular recess in the bracket 96. The cylindrical sleeve 136 is also guided by pins 138 that extend into apertures in the bracket 96. The sleeve 136 is urged downwardly by springs 140 40 mounted in apertures in the bracket 96 and bearing on the upper end of the sleeve, the downward movement of which sleeve being limited by a shoulder 142 formed thereon engaging an annular plate 144 secured to the bracket 96. 45 50

The seal receiving and applying devices which are equally spaced about the periphery of the table 36 also successively cooperate with a vertically reciprocating cutting and stamping device 148 (Figs. 1, 2 and 6,) located at the front of the machine. This cutting and stamping device is actuated in timed relation to the table 36 so that each successive movement of the table brings 55 one of the applying devices 184 into registry therewith. The seals are cut from a strip s' of suitable material, which strip is fed in timed relation to the reciprocating movement of the cutting and stamping device 148 so that during a period of retraction of such

device, the forward end of the strip is advanced into position to be acted upon by the cooperating devices. The end of the strip is guided into position by guide ways 150 formed in a collar 152, which is secured to the upper end of an elongated cylindrical bushing 154, that in turn is secured in an aperture in a bracket 155 projecting from the frame of the machine. When the seal applying device 184 is brought into registry with the cutting and stamping device 148, a sleeve 156 thereof is depressed into contact with a cutting block 158 secured to the collar 152. Such movement of the sleeve also depresses an upwardly spring pressed 60 plunger 160 by the engagement of a shoulder 162 formed on the sleeve 156 with the head of the plunger 160. The shoulder 162 and the head of the plunger 160 are maintained in engagement by a spring 164 coiled about 65 the shank of the plunger and interposed between a shoulder 166 on the sleeve 156 and a sleeve 168 secured to the shank of the plunger. The sleeve 156 is normally maintained in retracted position by a spring 170 70 coiled about a reduced portion of the sleeve and interposed between a nut 171 threaded on the end thereof and a disk 172 secured to the table 36. The sleeve 156 and consequently the plunger 160 are depressed by a 75 leaf spring 174 during the down stroke of the plunger 70 by the outer end of the spring being brought into engagement with the upper end of the sleeve 156. This leaf spring is secured at its inner end to a 80 bracket 176 which in turn is secured to the plunger 70. The outer end of the leaf spring is provided with an aperture 178 to receive the upper end of the plunger 160, so that the spring itself does not act to depress the plunger. Upon the up stroke of the cutting and stamping device, a circular 85 shearing edge 180 on the upper end of a sleeve 182 cooperates with a corresponding shearing edge on the block 158 to cut a circular blank from the strip s' . Immediately thereafter a stamping member comprising a sleeve 186 is forced upwardly into the position shown in Fig. 6, which cooperates with the block 158 to form a flange on the blank 110 and thereby complete the formation of the seal. The upturned flange on the seal usually is very narrow, only approximately one-thirty second of an inch, so that the inside diameter of the lower extension on the 115 part 156 is made about one-sixteenth of an inch smaller than the inside diameter of the part 158. 120

Upon the retraction of the seal receiving and applying device 184 and the stamping 125 member 186, a plunger 188 that is axially mounted in the member 186 presses the seal against the plunger 160 by the action of its spring 190 until the member 186 has become 130 disengaged from the seal. The seal is then

held in the receiving and applying device by frictional contact between the end of the sleeve 156 and the flange of the seal. The plunger 188 is then carried downwardly by 5 the member 186 and in unison, therewith, the disk cutting sleeve 182 is also carried downwardly. To effect the operations described of the parts of the cutting and stamping device, the stamping member 186 10 is secured in a recess in the upper end of a plunger rod 192 which is actuated by a cam lever 194 (Fig. 2) to which it is connected through a link 196. The lever 194 is pivoted at 198 on a bracket secured to 15 the frame of the machine and its inner end is provided with a cam roll which engages a groove in a cam 200. The retraction of the plunger rod 192 acts near the limit of its down stroke to retract the cutting member 182 by the engagement of a collar 194 formed on the rod with an abutment 196 formed within a sleeve 198 to the upper end of which sleeve the cutting member 182 20 is secured. Upon the up stroke of the plunger rod 192 a spring 204 which is coiled about the rod and is interposed between a collar 205 thereon and the abutment 196 on the sleeve 198 acts to bring the cutting edge of the member 182 into operative engagement with the cutting edge of the cutting block 158, the upward movement of 25 said cutting member 182 being limited by the engagement of a shoulder 206 thereon with the end of the collar 152.

30 The strip 's' is fed to the cutting and stamping devices by means of a feed roll 210 which cooperates with a table 212, over which table the strip is fed from a roll R mounted between brackets 214 secured to the 35 frame of the machine. The feed roll 210 is urged downwardly toward the table by being secured to an arbor 216, the ends of which extend through and are journaled in downwardly spring pressed blocks 218 that 40 are acted upon by springs 220 coiled about screws 222 which extend through apertures in the blocks and are threaded into the brackets 214. The intermittent movement is imparted to the feed roll 210 by a gear 45 224 secured to one end of the arbor 216 which, through gears 226 and 228 is driven by a gear 230. The gear 230 is loosely mounted on a stud 232 secured to one of the brackets 214, and said gear carries 50 a ratchet wheel 234. This ratchet wheel is actuated to drive the gears by means of a pawl 236 pivoted on the upper end of a lever 238, which in turn is pivoted on the stud 232. The lever 238 is actuated 55 by a cam lever 240 pivoted at 242 on the frame of the machine, the lever 238 being provided with a slot at its lower end which is engaged by a pin 244 on the upper end of the cam lever. The cam roll 246 on the 60 cam lever 240 engages the groove of a cylinder

cam 248 that is carried by a continuously rotating shaft 250 journaled in bearings in the frame of the machine and driven by a sprocket wheel 252 thereon, which is connected by a sprocket chain 254 to a sprocket wheel 256 on the main shaft 10.

It will be understood, that as the seal receiving and applying devices are brought into registry with the cutting and stamping device 148 that they will successively receive completed seals and thereafter successively bring them into position so that their flanges accurately register with the scoring formed in the cushioning members of the bottle caps. When a seal has thus been positioned, a downwardly spring pressed plunger 258 (Fig. 2) mounted in the bracket 176, is carried downwardly to engage and depress the plunger 160 of the seal receiving and applying device against the action of the spring 164, so that the flange of the seal is accurately and firmly pressed into the cushioning member. The fact that the plunger 258 is spring pressed downwardly ensures a dwell in the application of pressure to the seals and thus permits the escape of air pocketed under the seal and which otherwise might unseat the seal. In order to insure that the seals will be firmly applied to the cushioning members of the caps after being acted upon by the plunger 258, they are successively advanced to register with the seal setting device 64. This device comprises a block 260 (Fig. 10) mounted to slide upon a bolt 262 threaded into an aperture in a bracket 264 secured to the plunger 70. This block is arranged to adjust itself to the top surface of the seal and apply a decided pressure thereto during the down stroke of the plunger 70 by means of a spring 266 coiled about the bolt 262 and interposed between the bracket 264 and the block 260. The downward movement of the block 260 on the bolt 262, during the up stroke of the plunger 70, is limited by the head 268 at the lower end of said bolt.

After the seals have been acted upon by the setting device 64, the bottle caps are successively advanced into alignment with the chute 66 at which time they are elevated above the pockets in the table 34, preparatory to their being discharged into the chute 66. To this end, the bottom of each pocket in the table 34 consists of the top surface of a vertically sliding block 270 (Fig. 8), the lower end of which block is provided with a cam surface 272 that engages a stud 274 projecting upwardly from the table 34 at a point in alignment with the chute 66, so that as the pockets approach this point, the blocks 272 ride up on the stud 274 to elevate the caps. The caps are then discharged into the chute by means of a finger 276 that is secured to a rod 278 pivotally mounted in

brackets on the frame of the machine. This finger is normally held against a stop 280 on the frame of the machine by a spring 282 coiled about the rod 278. The finger 276 is actuated to discharge the caps into the chute 66 by means of a stud 282 secured to the plunger 70, which, upon the down stroke of said plunger, engages a pin 284 projecting from the rod 278, thereby actuating the finger to discharge the caps. After a pocket passes by the stud 274 its block 272 is permitted to drop by gravity to its normal position. To assist in securing accurate registration between the pockets in the carriers or turrets 36 and 34, the carrier 36 is provided with a series of holes 289 which are bushed to receive a pin 291 projecting downwardly from a short lateral extension of the arm 176. This pin enters one of the holes 289 at each downward stroke of the plunger and corrects any inaccuracy in the registration of the pockets in the two carriers.

After the caps have been discharged by the ejector 276 the plugs 270 in the pockets 52 in the carrier 34 may remain in their raised positions, and in order to ensure their return to the proper positions, a pin 293 is secured in a bracket 295 carried by the plunger or head 70 in the proper position to strike each plug 270 and force it downwardly before it arrives in position to receive another bottle cap.

Having thus described my invention I claim as new and desire to secure by Letters Patent:

1. A machine for applying seals to bottle caps or the like having in combination, a horizontal rotary carrier provided with a plurality of pockets equally spaced about the periphery thereof capable of receiving caps provided with cushioning members, means for intermittently rotating the carrier, a vertical plunger extending axially through the carrier, means for reciprocating the plunger in timed relation to said intermittent movement of the carrier, a rotary tool carried by the plunger for forming an annular scoring in the cushioning members as the caps are successively presented thereto by the carrier, and means for rotating said tool comprising a vertically stationary gear having a vertical axis connected to said tool through telescoping members.

2. A machine for applying seals to bottle caps or the like having, in combination, a horizontal rotary carrier provided with a plurality of pockets equally spaced about the periphery thereof for receiving caps provided with cushioning members, means for intermittently rotating the carrier, a tool adapted to be rotated and vertically reciprocated to form an annular scoring in the cushioning members as the caps are presented thereto, means for reciprocating the

tool in timed relation to the intermittent movement of the carrier, and means for rotating said tool comprising a vertically stationary gear having a vertical axis, said gear being connected to said tool through 70 telescoping members.

3. A machine for applying seals to bottle caps or the like, having, in combination, a carrier provided with a plurality of pockets to receive bottle caps having cork disks 75 therein, means for intermittently moving said carrier, a cutter for scoring the cork disks in said caps, a plunger movable relatively to said carrier for forcing said cutter into said disks, a rotary shaft carried by 80 said plunger and supporting said cutter, a thrust bearing between said shaft and plunger for transmitting motion to said shaft to force the cutter into said disks, and means for rotating said shaft about its axis. 85

4. A machine for applying seals to bottle caps or the like, having, in combination, a carrier provided with a plurality of pockets to receive bottle caps having cork disks 90 therein, means for intermittently moving said carrier, a cutter for scoring the cork disks in said caps, a plunger movable relatively to said carrier for forcing said cutter into said disks, a rotary shaft carried by 95 said plunger and supporting said cutter, a thrust bearing between said shaft and plunger for transmitting motion to said shaft to force the cutter into said disks, a driving member on said shaft, and connections between said member and a driving 100 member rotating in fixed bearings for driving said shaft.

5. A machine for applying seals to bottle caps having cork disks therein, comprising, in combination, a carrier having pockets 105 to receive said bottle caps, means for delivering said caps to said carrier, a plunger for forcing said caps into said pockets, a reciprocating and rotating cutter for scoring said disks, means for forming and presenting seals for application to said disks while the caps are in said pockets, a plunger for forcing said seals into said disks, and a single operating mechanism for giving said plunger and cutter 110 their operating strokes. 115

6. A machine for applying seals to bottle caps having cork disks therein, comprising, in combination, a rotary horizontal carrier having pockets to receive said bottle caps, 120 means for delivering said caps to said carrier, a plunger for forcing said caps into said pockets, a reciprocating and rotating cutter for scoring said disks, means for forming and presenting seals for application to said disks while the caps are in said pockets, a third plunger for forcing said seals into said disks, and a single operating mechanism for giving said plunger and cutter 125 their operating strokes, said 130

mechanism comprising a plunger having an operative connection with the aforesaid plungers and cutter and extending axially through said carrier, and means below said carrier for operating said third plunger.

7. A machine for applying seals to bottle caps having cork disks therein, comprising, in combination, a carrier having pockets to receive said bottle caps, means for positioning seals for application to the cork disks of said caps while they are in said pockets, a plunger for forcing said seals into said disks, and a mechanism for operating said plunger and giving it a substantial dwell while in contact with a seal forced into one of said disks to press the seal firmly thereinto.

8. A machine for applying seals to bottle

caps or the like having, in combination, a horizontal rotary carrier having a plurality of pockets equally spaced about the periphery thereof for receiving bottle caps provided with cork disks, means for intermittently rotating said carrier, a vertical plunger extending axially through the carrier, means below said carrier for reciprocating the plunger in timed relationship to said intermittent movements of the carrier, mechanism for scoring said cork disks including a rotary cutter arranged to be reciprocated by said plunger, and additional means for applying metallic seals to the cork disks so scored, said additional means including devices carried by said plunger.

CARL OSCAR BERG.
